Millard C. Short

United States Patent Office.

WILLARD C. SHORT, OF PROVIDENCE, RHODE ISLAND.

Letters Patent No. 105,004, dated July 5, 1870.

IMPROVED CHAIN-LINK.

The Schedule referred to in these Letters Patent and making part of the same

To all whom it may concern:

Be it known that I, WILLARD C. SHORT, of Providence, in the county of Providence and State of Rhode Island, have invented an improved Chain-Link; and do hereby declare that the following is a full and exact description, reference being had to the accompanying drawings making a part of this specification.

The nature of my invention consists in connecting the two curved ends used to form a link, by means of tubes whose calibre is about the same as the gauge of the wire used to form the bends.

To enable those skilled in the art to make and use my invention, I will proceed to describe its construction.

The drawings represent a chain formed of these links, one of them being shown in section, where the

two curved ends A and A', formed of solid wire, are connected to each other by the parallel tubes B and B', the curved ends being inserted and secured within the bore of the tubes. This mode of constructing a chain has many important advantages, and combines cheapness with durability.

What I claim as my invention, and desire to secure by Letters Patent, is—

The improved chain-link, consisting of the curved ends A and A', and the connecting-tubes B and B', fastened to each other, substantially as described.

WILLARD C. SHORT.
